Primary Examiner — Phillip S Hyder(74) *Attorney, Agent, or Firm* — Vedder Price PC(57) **CLAIM**

The ornamental design for an exercise bar attachment, as shown and described herein.

DESCRIPTION

FIG. 1 is a left side elevation view of the exercise bar attachment;

FIG. 2 is a front elevation view of the exercise bar attachment;

FIG. 3 is a top plan of the exercise bar attachment;

FIG. 4 is a rear elevation view of the exercise bar attachment;

and,

FIG. 5 is a bottom plan view of the exercise bar attachment. The broken lines depict portions of the exercise bar attachment in which the design is embodied that are not considered part of the claimed design.
